UNITED STATES PATENT OFFICE.

BENJAMIN FRANKLIN FISH, OF CHICAGO, ILLINOIS.

OPERATING MECHANISM FOR ROTARY OVENS.

No. 924,753.

Specification of Letters Patent.

Patented June 15, 1909.

Application filed June 29, 1908. Serial No. 440,856.

To all whom it may concern:

Be it known that I, BENJAMIN FRANKLIN FISH, a citizen of the United States, residing at Chicago, in the county of Cook, and State 5 of Illinois, have invented certain new and useful Improvements in Operating Mechanism for Rotary Ovens; and I do declare the following to be a full, clear, and exact description of the invention, such as will enable others skilled in the art to which it 10 pertains to make and use the same.

This invention relates to improvements in operating mechanism for rotary ovens.

The object of the invention is to provide 15 an auxiliary operating mechanism in connection with the main operating mechanism, and means whereby said main operating mechanism is thrown out of gear and said auxiliary mechanism simultaneously thrown 20 into gear, and vice versa, thereby permitting the rotary supporting mechanism within the oven to be operated by the auxiliary mechanism when desired.

With this and other objects in view, the 25 invention consists of certain novel features of construction, combination and arrangement of parts as will be more fully described and particularly pointed out in the appended claims.

30 In the accompanying drawings, Figure 1 is a front elevation of an oven showing the application of my invention thereto; Fig. 2 is a top plan view of the same showing the parts arranged as when operated by the 35 main driving mechanism; Fig. 3 is a horizontal sectional view on the line 3—3 of Fig. 1; Fig. 4 is a top plan view of a portion of the operating mechanism showing the arrangement of the clutch device when the parts are 40 operated by hand; Fig. 5 is a plan view of a modified form of hand operating mechanism; Fig. 6 is a front view of the same; and Fig. 7 is a plan view of another modified form of hand operating mechanism.

45 Referring more particularly to the drawings, 1 denotes the oven, which may be of the usual or any preferred construction and has in its front side a door, 2, having connected thereto a suitable opening and closing 50 mechanism, 3. Revolubly mounted in the top of the oven is a tray supporting shaft, 4, on the lower end of which and at a suitable position in the oven is mounted a supporting tray, 5, upon which the loaves of bread or 55 other material to be baked are placed, and by means of which they are revolved or car-

ried around in the oven during the baking process.

On the upper end of the shaft, 4, is fixedly mounted a worm gear, 6, with which is operatively engaged a worm, 7, mounted on the tray operating shaft, 8, which is journaled in suitable bearing brackets on the top of the oven. On the tray operating shaft is fixedly mounted a bevel gear pinion, 9, with which 60 is engaged a similar pinion, 10, fixed on the end of a main drive shaft, 12, which is formed in sections, each section of which is mounted in suitable bearing brackets, 13. On the section of the shaft opposite to that upon which the gear pinion, 10, is arranged, is fixed a driving pulley or gear, 14, which is connected by a driving belt or the like, to a suitable motor or source of power whereby said pulley end of the shaft is continuously driven. 65

On the inner end of the pulley section of the shaft, 12, is fixedly mounted one member, 15, of a clutch connection, the opposite member, 16, of which is slidably engaged with the inner end of the pinion section of the 70 main drive shaft, as shown. The member, 16, of the clutch is slidably connected to the shaft by means of a spleen or feather, whereby this section of the shaft is caused to turn with the clutch member when the latter is 75 shifted into engagement with the clutch member, 15, on the end of the constantly-driven section of the drive shaft.

On the forward end of the tray-operating shaft, 8, is slidably mounted one member, 17, 80 of a clutch connection, said member 17 being suitably keyed or splined to slide on the shaft, 18, and said clutch member is adapted to be brought into engagement with a clutch member, 18, which is fixedly mounted on the 85 adjacent end of a short shaft, 19, of an auxiliary operating mechanism. The shaft, 19, is mounted in suitable bearing brackets, 20, on the top of the oven, and on the outer end of said shaft, 19, is mounted a bevel gear 90 pinion, 20. The pinion, 20, is engaged with and operated by a pinion 21, on the end of a connecting shaft, 22, which is journaled in suitable brackets, 23, on the front of the oven and has mounted adjacent to its opposite end 95 a bevel gear pinion, 24, which is operatively engaged with a similar pinion, 25, on an auxiliary operating shaft, 26, which is mounted in a suitable bearing formed on an extension of one of the bearing brackets, 23, on the 100 front of the oven. On the shaft, 26, is mounted a hand wheel or other operating de- 105

vice 27, whereby the auxiliary operating mechanism may be actuated by hand power.

Pivottally mounted in any suitable manner upon the front or top of the oven is a clutch operating lever, 28, the inner end of which is 5 loosely engaged with the slidable member, 16, of the clutch mechanism in the main drive shaft. The clutch lever is provided with a laterally projecting arm or branch, 29, 10 the outer end of which is loosely engaged with the slidable member 17 of the clutch connection between the shaft, 19, and the tray operating shaft, 8, whereby when the lever is operated in one direction, the clutch 15 member, 16, will be thrown into operative engagement with the member, 15, of the main drive shaft, while the member, 17, will be disengaged from the member, 18, of the clutch connection with the tray operating 20 shaft, thereby simultaneously connecting said shaft with the main drive shaft and disconnecting the same from the auxiliary operating mechanism. In the same manner when the clutch lever is operated or swung in 25 the opposite direction, the sections of the clutch connection of the main drive shaft will be disconnected, while the clutch connection on the tray operating shaft will be simultaneously thrown into engagement with the 30 clutch member on the auxiliary operating mechanism, thereby connecting said tray operating shaft with the auxiliary operating mechanism and disconnecting the same from the main driving shaft. When the clutch 35 connections are thus arranged, the supporting tray may be operated by hand through the auxiliary operating mechanism to turn the same in either direction, thus providing for the quick removal of the goods from any 40 portion of the supporting tray.

In Figs. 5 and 6 of the drawings is shown a modified construction of the auxiliary operating mechanism, the latter being shown in this instance as having an auxiliary operating 45 shaft, 26, provided with a sprocket gear, 30, which is connected by a sprocket chain, 31, with a sprocket gear, 32, on the end of the short shaft, 19, which has a clutch connection with the tray operating shaft, 8, as hereinbefore described.

In Fig. 7 of the drawing is shown another modified form of the auxiliary operating mechanism in which a universal joint connection, 33, is provided between the ends of 55 the connecting shaft, 22, and the shaft, 19, which has a clutch connection with the shaft, 8, said universal joint connection taking the place of the bevel gears, 20 and 21, as shown in the first figures of the drawings.

60 From the foregoing description, taken in connection with the accompanying drawings, the construction and operation of the invention will be readily understood without requiring a more extended explanation.

65 Various changes in the form, proportion

and the minor details of construction may be resorted to without departing from the principle or sacrificing any of the advantages of the invention as defined in the appended claims.

Having thus described my invention, what I claim as new and desire to secure by Letters-Patent, is:

1. In an operating mechanism for rotary ovens, a tray operating mechanism, a main power operated drive shaft, an auxiliary hand operated driving mechanism, clutches arranged in said driving mechanism, and a forked shifting lever connected with said clutches, whereby one of said mechanisms is 75 thrown into gear and the other simultaneously thrown out of gear, and vice versa.

2. In an operating mechanism for rotary ovens, a tray operating mechanism, a main drive shaft formed in sections, a clutch connection between said sections, an auxiliary operating mechanism, a clutch mechanism between said auxiliary mechanism and said tray operating mechanism, and means to simultaneously operate said clutches to 85 throw said driving mechanism into gear and said auxiliary operating mechanism out of connection with said tray operating mechanism, and vice versa.

3. In an operating mechanism for rotary ovens, a tray operating shaft, a main drive shaft formed in sections, a clutch connection between said sections, an auxiliary operating mechanism, a clutch connection between 95 said auxiliary mechanism and said tray operating shaft, and a lever having means to engage and operate said clutches to simultaneously throw said main driving shaft into gear and said auxiliary operating mechanism out of gear with said tray operating shaft, 100 and vice versa.

4. In an operating mechanism for rotary ovens, a supporting tray, a tray supporting shaft, a tray operating shaft geared to said supporting shaft, a main drive shaft formed 110 in sections, a clutch connection between said sections, means whereby one section of said driving shaft is geared to said tray operating shaft, an auxiliary operating mechanism, a clutch connection between said auxiliary 115 mechanism and said tray operating shaft, and a clutch operating lever adapted to be moved in one direction to engage the clutch connection between the sections of said main shaft and to simultaneously disengage the 120 clutch connection between said auxiliary driving mechanism and said tray operating shaft and to be moved in the opposite direction to disconnect the clutch mechanism of the main drive shaft and to simultaneously 125 engage the clutch connection between said auxiliary mechanism and the tray operating shaft, substantially as described.

5. In an operating mechanism for rotary ovens, a tray operating shaft, a main drive 130

shaft formed in sections geared thereto, a clutch connection between said sections of the main shaft, an auxiliary operating mechanism comprising a short shaft, a clutch connection between said shaft and the tray operating shaft, a manually operated shaft, means to connect said shaft with the clutch shaft of said auxiliary mechanism, and a clutch operating lever adapted to simultaneously operate the clutch connections between said sections of the main drive shaft and between said tray operating shaft and auxiliary mechanism to throw said parts into and out of gear, substantially as described.

6. In combination with an oven, a tray operating shaft arranged on the oven, a main drive shaft for operating the tray operating shaft, gearing for connecting the two shafts, a manually operated auxiliary drive shaft, gearing for connecting the auxiliary shaft to the tray operating shaft, and means for si-

multaneously connecting one of the drive shafts with the tray shafts and disconnecting the remaining shaft therefrom.

7. In combination with an oven, a tray operating shaft arranged on the oven, a main drive shaft formed in sections for operating the tray operating shaft, coacting clutch parts secured to the adjacent ends of the sections, gearing for connecting the drive shaft to the tray operating shaft, an auxiliary drive shaft, coacting clutch parts for connecting the auxiliary drive shaft to the tray shaft, and a pivoted forked lever for simultaneously actuating the clutch parts. 25 30 35

In testimony whereof I have hereunto set my hand in presence of two subscribing witnesses.
